UNITED STATES PATENT OFFICE.

MICHAEL ANDREW DROITCOUR, OF DELPHOS, OHIO.

MECHANISM FOR REGISTERING SHEETS.

1,299,920.

Specification of Letters Patent.

Patented Apr. 8, 1919.

Application filed March 21, 1918. Serial No. 223,755.

To all whom it may concern:

Be it known that I, MICHAEL A. DROITCOUR, a citizen of the United States, residing at Delphos, in the county of Van Wert 5 and State of Ohio, have invented certain new and useful Improvements in Mechanism for Registering Sheets; and I hereby declare that the following is a full, clear, and exact description thereof, reference being had to the accompanying drawings, which form part of this specification.

This invention is a novel improvement in mechanisms for registering sheets of paper and the like in position to be fed to mechanism for operating thereon; such as printing presses; and the invention has particular reference to means for registering the sheets fed to such presses in position to be seized by the grippers of the impression 20 cylinders.

My invention provides means for both side registering and front registering the sheets; and for supporting the main operative parts of such mechanism and operationally connecting same in such manner that they cannot get out of time; such register operating mechanisms being practically movable as a unit and being preferably mounted in a support or frame which can 25 be moved or swung up out of the way at any time, if the operator for any reason wishes it. Heretofore the front registering devices and the side registering devices have been usually separately supported and operated so that they are liable to become disarranged or thrown out of time when one or the other or both are moved out of the way; but in my invention the registering mechanisms are kept in time both when in 30 operative position and when out of such position, so that in all positions the register actuating mechanisms—whether raised or lowered, or in operative or inoperative positions—will remain in time, and thus save 35 time and annoyance in adjusting the various registers to act in proper time as required for feeding of the sheets.

The invention includes novel means for operating the side registering devices and 40 the front registering devices; also novel means whereby the sheets may be registered either on the right hand or feeder side, or on the left hand or gear side, of the press as may be desired; novel means whereby the 45 sheet registering devices can be readily swung up or moved out of the way as a unit

whenever it is desired to make ready the press, or get at the sheet gages, or cylinder, or to raise the feed table, without destroying the time relation or driving means of 60 such regulating mechanisms; also certain minor novel features of construction and novel combinations of parts hereinafter explained.

I will explain the invention with reference to the accompanying drawings which illustrate one practical embodiment thereof; but I do not consider the invention restricted to the particular construction of parts illustrated in said drawings, as these 70 may be varied while retaining the essential novel characteristic features and advantages of the invention; and I therefore refer to the claims for summaries of the essentials of the invention and novel combinations and 75 novel constructions of parts for which protection is desired.

In said drawings:

Figure 1 is an end elevation of the sheet registering mechanisms viewed from the 80 side of the press, and conventionally illustrating part of the feed board and portions of the press adjacent the registering mechanisms.

Fig. 2 is an enlarged sectional view on line 2—2, Fig. 3.

Fig. 3 is a top plan view of the registering mechanisms.

Fig. 4 is an enlarged detail top plan view of parts shown in Fig. 2.

Figs. 5, 6, 7 and 8 are enlarged detail views of parts of the side registering devices.

Fig. 9 is a reverse view of the cam member 4a.

Figs. 10 and 11 are enlarged top and end views of one of the side registering gages.

I will explain the invention as employed in connection with a sheet printing press having a rotatable impression cylinder to 100 which the sheets are supplied over a feed table, and their forward edges are alined against front sheet gages in position to be taken by the grippers on the cylinder by front registering devices substantially in the 105 manner described in my Patent #1,196,934 of Sept. 5, 1916. Obviously, however, the invention is usable in connection with other kinds of presses and machines to which it is desired to supply sheets in a uniform accurately positioned manner.

Various mechanisms have been heretofore

employed for front registering the sheets against the front gages, and various means have been used to register the sheets against either right or left hand side gages, and 5 effective front and side registering means are shown in my said patent. My present invention therefore has particular reference to the means whereby the sheets may be alined against both front gages and right or 10 left side gages, as may be desired or required by the work being performed on the press, and to render all such mechanisms easily adjustable as a unit into and out of operative position without disturbing their relative adjustment or time.

As conventionally illustrated in Fig. 1, the impression cylinder C is provided with usual grippers c, and the sheets are supplied thereto from a table T, which may be of 20 any desired construction, and the sheets may be fed forward over said table, either automatically or by hand. The front edge of each sheet is arrested by front sheet gages of any suitable kind—(preferably like those 25 shown in my aforesaid patent, and indicated at G in the drawings)—until the sheet is taken by the grippers c. These parts may all be of any desired construction, and arranged to operate in the usual manner and 30 *per se* form no part of the present invention.

In order to properly position the sheet S on the table T, it is not only desirable that the forward end of the sheet be alined against the gages G by suitable front registering devices, preferably such as are described in my aforesaid patent, but it is also desirable that the sheet be alined against 35 side gages indicated at g, which may be also of any suitable desired construction, but 40 preferably such as are hereinafter described, and it is desirable in some cases to aline the sheets against side gages at the right-hand or feeder side of the press, and in other cases desirable to aline the sheets against like 45 gages at the left hand or gear side of the press.

In the embodiment of the invention illustrated in the drawings the main operative parts of the registering devices are mounted 50 in a tiltable frame or support arranged above the cylinder.

As shown, this supporter frame preferably comprises a centrally disposed member 1 and two end members 1^x, substantially similar to member 1, which members may be cast; and each member 1, 1^x, is fastened at one end upon a shaft 1^a journaled in brackets 1^b of any suitable kind attached to the side frames of the press, as indicated in 55 Fig. 1; the other ends of the members are connected by a tie rod 1^w and a pair of parallel rods 1^c.

A shaft 2 is journaled in members 1, 1^x intermediate the shaft 1^a and rods 1^c, and 60 on said shaft is fixed a gear 2^a which may be

driven by any suitable means. As shown gear 2^a meshes with a gear 2^b loosely mounted on shaft 1^a, which may be driven by a train of gears C', C², C³, C⁴ and C⁵ from the shaft of the cylinder C as indicated in dotted lines 70 in Fig. 1. The gearing should be such that if the invention is applied to a two revolution printing press the shaft 2 will be turned once for each two revolutions of the cylinder C.

On the shaft 2, preferably adjacent the intermediate member 1, is keyed a disk 3, which has two diametrically opposite notches 3^a and 3^b in its periphery, either of which may be engaged by a dog 4 pivoted on a 80 cam-member 4^a that is loosely mounted on the shaft 2 beside the disk 3. Said cam member has on its face opposite the disk 3 an eccentrically disposed race-cam portion 4^b which is engaged by a roller 4^c on a 85 slideable rack bar 4^d that has a bifurcated end 4^e loosely embracing the shaft 2, and its toothed portion is guided by a bracket 4^f attached to the rod 1^c adjacent the cam.

The rack 4^d meshes with a segment 5^a pivoted on a stud 5, attached to member 1; and oscillates this segment as rack 4^d is reciprocated by the cam 4^b. Pivoted on stud 5 and attached to the segment 5^a is a second segment 5^b which meshes with a rack 5^c on a 95 casting 5^d attached to a rod 5^e which is slidably mounted in the end castings 1^x and lies parallel with and intermediate the rods 1^c, (see Figs. 4 and 6). This rack 5^c and rod 5^e will be reciprocated endwise when rack 100 4^d oscillates the segments upon the rotation of cam 4^b.

Upon the rods 1^c are mounted the actuating members of devices for side registering the sheets, and to enable the sheets to be 105 registered at either side of the machine I provide two sets of side registering devices, one adjacent each member 1^x.

As shown more particularly in Figs. 5, 6 and 8 each of such devices comprises an 110 H-shaped casting 6 having opposite sleeves slidably mounted upon the bars 1^c and connected by a bridge piece 6^a. Pivoted from and between the sleeves 6 at opposite sides of the bridge piece 6^a are 115 double inverted U-shaped members 6^b and 6^c which are pivoted at their upper ends on pins 6^d and 6^e to ears on sleeves 6. The legs of members 6^b, 6^c depend between the sleeves 6 and below the rods 1^c and are pivotally connected at their lower ends to a brush-member 6^f which is suspended thereby.

Slidably mounted upon the rods 1^c is a T-shaped member 6^g which is adjustably connected with the rod 5^e by a set screw 6^h so 125 that it will be reciprocated by and with the rod 5^e. This member 6^g has a central extension 6ⁱ that extends between the sleeves 6 and between the arms of the levers 6^b and this extension has pins 6^k on its sides which 130

engage inclined slots 6^m in the legs of the members 6^t, see Fig. 5.

As a result of this construction when the member 6^t is moved toward the member 6 5 the pins 6^k engaging the slots 6^m cause the members 6^b, 6^c to swing so as to lower the brush-member 6^t into engagement with a sheet of paper S lying upon the bar 7 and move the sheet sidewise into engagement 10 with the side register gages. When the rod 5^e moves the casting 6^t away from the casting 6 the pins 6^k within slot 6^m swing the lever 6^c and bar 6^a upward and disengage same from the sheet.

15 The extent of lowering of the brush-member 6^t or the pressure thereof upon the sheet S can be regulated by means of a screw 6^p which is tapped through an angular extension 6ⁿ on the upper end of the member 6^c 20 overlying the bar 6^a and screw 6^p is provided with a lock nut 6^r. When the rod 5^e is moved so as to cause the lowering of the brush-member 6^t, as described, it can be lowered until the screw 6^p engages the member 25 6^a and then further movement of the bar will cause the brush-member to travel linearly with the bar 5^e.

The lower surface of the brush-member 6^t 30 may be provided with any suitably frictional rubbing or sheet engaging surface, preferably a brush 6^g, as indicated in the drawings. Two sets of such sheet engaging devices are mounted on the rods 1^c at opposite sides of the central member 1; and 35 either of these can be adjusted toward or away from the member 1. Either of such sheet engaging devices can be operated, according to whether the sheet is to be registered at the right or left hand side.

40 The members may be adjusted to any desired position on the bars 1^c and rod 5^e; and then member 6^t fastened to the rod 5^e, when adjusted, by means of thumb-screw 6^h.

The casting 6 may be provided with a 45 yielding frictional device (such as spring 63 shown in my aforesaid patent) to prevent its moving with the casting 6^t until after the brush-member has been either varied or lowered, then it will move with the casting 50 6^t.

To assist the said devices in side registering the sheets I preferably use a transverse slide bar 7 underlying the sheet and set in a channel in the table T. This bar 7 may 55 also be operated by and from the rod 5^e, as indicated in Figs. 5 and 7. For this purpose an upstanding bracket 7^a is attached to the bar 7 near one end thereof to which is pivoted a finger 7^b, which projects above the rod 5^e and is adapted to engage a notch 5ⁿ in the rod 5^e, the finger being yieldingly pressed toward the rod and into engagement with said notch by spring 7^c. If, for any reason, the bar 7 should be slightly displaced relatively to the rod 5^e when the registering de-

vices are raised, (as hereinafter explained) then when the registering devices are lowered, the rod 5^e would press the finger 7^b outward, and the latter finger would ride yieldingly against the rod 5^e until the notch 5ⁿ 70 therein engages the finger; then the slide 7 would be locked to and move with the rod 5^e and properly coat with the brush 6^g in side registering the sheet. The sheet is lightly grasped by and between the brush 75 member and bar when the latter are moved in the proper direction and drawn up against the proper side guide and registered thereagainst.

If the sheets are to be registered against 80 the right hand side gages the set of left hand members can be moved out of operative position and disengaged from rod 5^e by loosening screw 6^t. If the sheet is to be registered against the left hand side gages, the 85 right hand members could be similarly adjusted out of operative position and disengaged from rod 5^e.

Side register gages 9 of any suitable kind 90 may be used to properly position the side edge of a sheet brought thereagainst relative to the printing surface on the cylinder, as described in my Patent #1,196,934. Preferably I employ side registering gages, 95 shown in Figs. 3, 10 and 11. Each side registering gage comprises a slotted plate 9 adjustably attached to the table T by suitable screws 9^e and having a pair of side lugs 9^b in which is rotatably mounted a screw rod 9^e which can be turned by hand. 100 Threaded on this screw is a stud 9^c on a member 9^d which projects across the bar 7 and has attached to its upper side parallel arms or strips 9^h carrying sheet stops 9^f on their outer ends. A side guide adjusting fork 9ⁱ 105 attached to the stud 9^c provides a double bearing on screw rod 9^e for the member 9^d thereby causing a more positive positioning of the sheet stop 9^f.

Right and left hand side gages are provided but when one is used the other may be removed out of the way. Such gages can be easily attached or detached from the table as required. The member 9 and the parts attached thereto can be longitudinally adjusted by loosening screws 9^e as is obvious; and when the member 9 is fixed the member 9^f can be further accurately adjusted to a limited extent by turning the screw 9^e. 110

Upon the shaft 2 may also be mounted devices for front registering the sheets against gages G or other suitable stops. Preferably I use front registering brushes as described in my aforesaid patent; and accordingly segmental brushes 31 are shown mounted on shaft 2 and adapted to coat with the segmental brushes 20 attached to the cylinder C; see Fig. 1. The said brushes are preferably constructed and adapted to coat and front register the sheet against the gages G 115 125 130

substantially as described in my aforesaid patent. I do not herein claim the front registering devices *per se*.

It will be observed that I have provided 5 mechanisms whereby the sheet may be registered both against the front gages and against the desired side gages; and that such mechanisms are so mounted that they can be moved out of the way as a unit when making ready, or for any other desired reason, such as for inspection or adjustment of the parts, and without any of the parts becoming disarranged or out of time.

When the parts are in the position shown 15 in full lines in Fig. 1, dog 4 being engaged with the notch 3^a; the rod 5^e and the connected members 6^f will be reciprocated as shaft 2 is revolved; and the gear and parts are so timed and adjusted, that after a sheet 20 S has been fed forward on the table T to the front gages G and after it is positioned against such gages by the front registering devices; the proper side registering device is moved and draws the sheet either to right 25 or left against the proper side registering gage, as may be desired.

As stated when the sheet S is brought forward by the tapes it is first registered against the front gages by means of one of 30 the brushes 2^a contacting with one of the brushes 31, which in co-action with the brush 20 moves the sheet up against the front gages G, then the sheet is moved by the brushes 6^g and plate 7 against the side gages 35 and thereafter is again front registered by the action of the second brush 31 with the brush 20; so that each sheet is first front registered, then side registered, and then again front registered before it is taken by 40 the cylinder grippers; substantially as described in my aforesaid patent.

Assuming that when dog 4 is in engagement with the notch 3^a in disk 3 the right hand side member will be operated to register the sheet against the right hand side gage. If it should afterward be desired to register the sheets against the left hand side gages; the operator should disengage the right hand side registering brush member 45 from rod 5^e and move the same to one side out of the way; then move the left hand brush member into operative position and fasten it to rod 5^e; then disengage the dog 4 from notch 3^a, and turn the cam disk 4^a 50 manually a one-half revolution until the dog 4 engages with the notch 3^b. Then when the machine is again started in operation the devices will register the sheets against the left hand side gage. If it be afterward desired 55 to again register sheets against the right hand side gage the left hand side registering member should be disconnected from rod 5^e, and the right hand side registering member connected therewith; then dog 4 should be 60 disconnected from the notch 3^b and the cam 65

disk 4^b turned until the dog 4 engages with notch 3^a, whereupon when the machine is operated the sheets will be registered against the right hand side gages.

The invention provides a very simple 70 means for imparting motion to the side registering devices and quickly adjustable means for changing the side register from the right hand side to the left hand or feeder side.

The frame carrying the registering devices may be supported in proper operative position by any suitable means. As shown bolts 1^u are tapped through lugs 1^v on the side members 1^x and engage the top of the caps 80 which fit over the jaws on the adjacent side frames of the machine. When it is desired to make ready the machine or to pack the cylinder, or to raise the table T, the frame and all the registering mechanisms thereon 85 as a unit can be bodily moved out of the way by swinging the frame back upon the shaft 1^a as a hinge; and as in my invention all the effective operating parts of such mechanisms above the sheet are mounted upon the movable frame and depend for their operation 90 upon the same mechanisms; they can be handled as a unit, and may be moved with the frame into or out of operative position without becoming relatively displaced or out of 95 time.

What I claim is:

1. In combination a feed table having side gages; a tiltable frame mounted above the table; a rotatable shaft mounted in said 100 frame; means on said frame for registering sheets against either side gage, and means for actuating said registering means from said shaft; said shaft and means being movable with the frame into or out of operative 105 position.

2. In sheet registering mechanism the combination with sheet taking means and a feed table having side gages; of a movable frame above the table; a rotatable shaft 110 mounted in said frame; means on said frame for registering sheets against either side gage; and means for actuating said moving means from said shaft whereby said registering means is kept in proper time whether 115 in or out of operative position; said means and shaft being movable with the frame independently of the table into or out of operative positions.

3. In combination a movable frame, a rotatable shaft thereon, a side registering device slidably mounted on said frame, a reciprocatory rod also mounted on said frame and detachably engaged with said registering device, and means for reciprocating said 120 rod from the rotatable shaft, said devices being movable with the frame into or out of operative position.

4. In combination a movable frame, a rotatable shaft thereon, a registering de- 130

vice slidably mounted on said frame, a reciprocatory rod detachably engaged with said registering device, a cam on said shaft, adjustable means for locking the cam to the shaft, so as to change the relation of the cam to the shaft, means for reciprocating said rod from the said cam.

5. In combination a movable frame, a rotatable shaft thereon, a side registering device 10 vice slidably mounted on said frame, a reciprocatory rod detachably engaged with said registering device, a reciprocatory rack bar, a cam on said shaft actuating said rack bar, and means for reciprocating said rod by said rack bar.

6. In combination a side gage; a hinged frame, a rotatable shaft mounted in said frame, side registering devices slidably mounted on said frame, a reciprocatory rod connected with said registering devices, a rack connected with said rod, an oscillating segment engaging said rack; a slidable rack actuating said segment, and a cam on said shaft engaging said slidable rack.

20 7. In combination with a feed table and side registering gage; a frame hingedly mounted above the table, a rotatable shaft mounted in said frame, a side registering device slidably mounted on said frame, a reciprocatory rod connected with said registering device, a rack connected with said rod, a cam on said shaft; means for operating said rod from said cam; a notched disk fixed on said shaft beside the cam, and means for detachably locking the cam to said disk.

30 8. In sheet registering mechanism having front and side gages; a movable frame; a rotatable shaft mounted in said frame; means on said frame for moving sheets against the front gage, and means on said frame for moving sheets against the side gage; and means on said frame for actuating each of said moving means from said shaft.

40 9. In combination with sheet taking means, front and side gages; of a movable tiltable frame; a rotatable shaft mounted in said frame; means on said frame for moving sheets against the front gage; means on said frame for moving sheets against the side gage; and means for actuating each of said moving means from said shaft; said means being movable with the frame into or out of operative positions.

50 10. In combination with sheet taking means, and a feed table having side gages; of a tiltable frame above the table; a rotatable shaft mounted in said frame; means on said frame for moving sheets against a side gage, and means for actuating said registering means from said shaft; said shaft and means being movable with the frame into or out of operative positions.

60 11. In sheet registering mechanism the

combination with sheet taking means and a feed table having side gages; of a tiltable frame above the table; a rotatable shaft mounted in said frame; means on said frame for moving sheets against the side gages; and means for actuating said moving means from said shaft whereby said means is kept in proper time whether in or out of operative position; said means and shaft being movable with the frame into or out of operative positions.

70 12. In combination a tiltable frame, a rotatable shaft thereon, a pair of side registering devices slidably mounted on said frame, a reciprocatory rod detachably engaged with said registering devices; and means for reciprocating said rod from the rotatable shaft.

80 13. In combination a movable frame, a rotatable shaft thereon; a pair of side registering devices slidably mounted on said frame; a reciprocatory rod detachably engaged with said registering devices; a reciprocatory rack bar; a cam on said shaft actuating said rack bar; and gearing between the rack bar and said rod for oscillating said rod from the rack-bar.

85 14. In combination a movable frame, a rotatable shaft thereon, a pair of registering devices slidably mounted on said frame; a reciprocatory rod detachably engaged with said registering devices; a reciprocatory rack bar; a cam on said shaft actuating said rack bar; adjustable means for locking the cam to the shaft so as to change the relation of the cam to the shaft; and gearing between the rack bar and said rod for reciprocating said rod from the rotatable shaft.

90 100 15. In combination with a feed table and side gages; a frame hingedly mounted above the table, a rotatable shaft mounted in said frame, a pair of side registering devices slidably mounted on said frame, a reciprocatory rod connected with said registering devices, a rack connected with said rod, an oscillating segment engaging said rack; a slidable rack actuating said segment, and a cam on said shaft engaging said slidable rack.

105 110 115 120 125 130 16. In combination with a feed table and side registering gages; a frame hingedly mounted above the table; a rotatable shaft mounted in said frame; a pair of side registering devices slidably mounted on said frame; a reciprocatory rod connected with said registering devices; a rack connected with said rod; an oscillating segment engaging said rack; a notched disk fixed on said shaft beside the cam, and means for detachably locking the cam to said disk.

17. In sheet registering mechanism, the combination of a reciprocating bar adapted to underlie the sheet, a reciprocating rod, a side registering device above the sheet oper-

- ated by said rod and a latch finger connected with said bar and adapted to be engaged with the said rod.
18. In sheet registering mechanism the combination of a table, a reciprocating bar mounted on the table; a frame above the table, a reciprocating registering device carried by said frame above said table, and means for actuating the said bar by and with the reciprocating registering device. 10
19. In sheet registering mechanism, a reciprocating bar adapted to underlie the sheet, a movable frame above the sheet, a reciprocating rod carried by said frame; a side registering device operated by said rod, means for oscillating said rod, and detachable connections between the said rod and said bar for actuating the latter from the former. 15
20. In sheet registering mechanism, the combination of a reciprocating bar adapted to underlie the sheet, a movable frame above the sheet, a reciprocating rod carried by said frame, a side registering device operated by said rod, means for oscillating said rod, and a latch finger connected with said bar and adapted to engage the said reciprocating rod when the frame is lowered, whereby the bar is moved by and with the rod. 25
21. A sheet gage comprising an adjustable member attached to the table, a rotatable but longitudinally immovable screw on said member, a member adjustably engaged with said screw and having a projecting portion, and sheet stops attached to said projecting portion. 30
22. A sheet gage comprising a member attachable to a table, a screw rotatably attached to said member, but confined against longitudinal movement, a member adjustably engaged with said screw and having a projecting portion, and sheet stops attached to said projecting portion. 40
23. A sheet gage comprising a member attachable to a table; a screw rotatably attached to said member, an adjustable member engaged with said screw and a sheet stop attached to said adjustable member, and an adjusting fork attached to the latter member and engaging the screw stem. 45
24. A sheet gage, comprising an adjustable slotted member, a screw rotatably mounted in said member, a slidable member having a stud engaged with said screw, and parallel arms connected with the slidable member, and sheet stops attached to said arms. 50
25. A sheet gage, comprising an adjustable slotted member but longitudinally movable, a screw rotatably mounted in said member, a slidable member having a stud engaged with said screw, a pair of parallel arms connected with the outer end of said slidable member, and sheet stops attached to the said arms. 60
26. In sheet registering mechanism having front and side gages; means for register- 65
- ing a sheet against the front gages, means for then registering a sheet against the side gages, and means for again registering the sheet against the aforesaid front gages before it is seized; said means being movable 70 as a unit into or out of operative position.
27. In sheet registering mechanism having front and side gages; means for registering a sheet against the front gages, means for then registering a sheet against the side 75 gage, and means for again registering the sheet against the aforesaid front gages before it is seized; said means being simultaneously movable into or out of operative position; and means whereby said mechanisms 80 are kept in proper relative timed relation whether in or out of operative position.
28. In combination with sheet taking means; and front and side gages; of means for registering a sheet against the front 85 gages, means for then registering a sheet against the side gage; and means for again registering the sheet against the aforesaid front gages before it is seized; said means being simultaneously movable into or out of operative position; and means whereby said mechanisms 90 are kept in proper relative timed relation whether in or out of operative position.
29. In sheet registering mechanism having front gages and side gages; a pivoted support; means on said support for registering a sheet against the front gages, and means on said support for registering a sheet against the side gages; said means being 95 movable with the support into or out of operative position; and driving means for the registering means mounted on the pivot of the swinging frame. 100
30. In sheet registering mechanism having front and side gages; a pivoted support; means on said support for moving a sheet against the front gage, means on said support for moving a sheet against the side gage; said means being movable with the support into or out of operative position; means carried by said support whereby said mechanisms are kept in proper relative 105 timed relation whether in or out of operative position; and driving means for the registering means mounted on the pivot of the swinging frame. 110
31. In combination with sheet taking means, and front and side gages; of a pivoted support; means on said support for moving a sheet against the front gage, means on said support for moving a sheet against the side gage; means on said support for actuating both of said mechanisms and whereby said mechanisms are kept in relative time 115 whether the support be adjusted to bring said means into or out of operative position; and driving means for the registering means mounted on the pivot of the swinging frame. 120
- 65

32. In combination with sheet taking means, and front and side gages; of a tilt-able frame; means on said frame for moving a sheet against the front gage, and means on said frame for moving a sheet against the side gage; said means being movable with the frame into or out of operative position; means carried by said frame for actuating both of said mechanisms; and driving means for the registering means mounted on the pivot of the swinging frame; whereby said mechanisms are kept in relative time whether the frame be raised or lowered.

33. In sheet registering mechanism the combination of a table, a reciprocating bar below the sheet, a reciprocating registering device above the sheet adapted to hold the sheet against said bar, means for reciprocating the said registering device, and devices for detachably connecting said bar to said reciprocating means whereby said bar is moved with the registering device.

34. In sheet registering mechanism, the combination of a reciprocating bar adapted to underlie the sheets, a reciprocating side-registering brush above the sheet adapted to press the sheet against said bar, means for reciprocating the said brush, and devices for detachably connecting said bar to said brush reciprocating means, whereby said brush and said bar may be moved together.

35. In combination a feed table having side gages; a movable frame mounted above the table; means on said frame for registering sheets against either side gage, and operative means on said frame for actuating said registering means, all said means being bodily mounted movable with the frame into or out of operative position without disturbing their relative adjustments.

In testimony that I claim the foregoing as my own, I affix my signature.

MICHAEL ANDREW DROITCOUR.
